UNITED STATES PATENT OFFICE.

HENRY C. JOHNSON, OF MEADVILLE, PENNSYLVANIA.

FIRE-PROOF SAFE.

SPECIFICATION forming part of Letters Patent No. 281,514, dated July 17, 1883.

Application filed May 16, 1883. (No model.)

To all whom it may concern:

Be it known that I, HENRY C. JOHNSON, of Meadville, in the county of Crawford and State of Pennsylvania, have invented certain improvements in Fire-Proof Safes and Vaults, of which the following is a specification.

My invention relates to fire-proof safes and vaults; and it consists in providing the same with exterior or exterior and interior refrigerating apparatus, whereby the same may be protected against fire and heat, as hereinafter fully explained.

The present invention is designed as an improvement upon that for which Letters Patent were issued to myself and another party, bearing date the 18th day of July, 1882, and numbered 261,461.

In the accompanying drawings, Figure 1 represents a perspective view of a safe embodying my improvements; Fig. 2, a vertical cross-section of the same, and Fig. 3 a perspective view of one form of gas-holder.

Hitherto safes and vaults have been provided with chambers or pipes embedded in their walls and charged with compressed gas, which, upon the fusion of a suitable alloy, was permitted to escape into the open air for the purpose of poisoning the air, to overcome burglars or to subdue flames about the safe or vault. In the patent hereinbefore referred to the gas-holder was placed within the safe and the gas permitted to escape from said holder into the safe upon the fusion of a button or hook having a low fusion or melting point, the idea being to cool the safe sufficiently to counteract the outside heat of the fire. It is now found that, as applied in the patent above referred to, the refrigerating device was not wholly sufficient for the purpose in view—first, because the cooling surface was not in the most available or serviceable form, and, secondly, because the walls, becoming heated through and through, would require a large volume of gas to be used and its action to be continued for a very long time. By the present plan I not only greatly increase the effectiveness of the gas in its cooling capacity inside the safe or vault, but also secure that effect from the outside of the safe, so that the walls cannot become heated as before.

Referring now to the drawings, A represents the safe or vault as a whole, which may

be of any suitable construction; and B, a gas-holder of any desired form, provided with one or more outlets, *a*, closed or sealed by means of a cap or plug, *b*, of any suitable alloy adapted to fuse or melt at a predetermined temperature. These holders are charged with a highly-compressed and preferably liquefied gas, carbonic acid gas being preferred because of its great compressibility and of its effect upon combustion, though other gases may obviously be used. The holders B should be made of flat form, either a pipe or series of pipes running back and forth in parallel branches, or a thin flat vessel corrugated or otherwise adapted to fit against a face or wall of the safe or vault or into the external panels thereof, the latter plan being convenient and desirable because requiring no additional space, or but very little, and affording a convenient means of retaining the holders in place.

The interior of the safe or vault may likewise be furnished with gas-holders, and these, like the outside ones, may be formed of tubes or of flat or corrugated plates.

It has been ascertained by practical experiment that if the liquefied gas be merely permitted to escape into an open space, and to expand therein, the refrigerating effect is comparatively slight; but if the gas-holder be made of such form as to present a large surface unobstructed by non-conducting surroundings, and this be placed within the safe or vault to be cooled, the expansion of the gas within the holder to supply the space left by escaping gas will produce a great degree of cold, thus causing the holder to act also as a cooler. The vent *a* is made small in order that the gas may escape slowly and in a fine stream, thus causing the flow to continue for a long time and the cooling action to be correspondingly maintained, the sudden expansion of the gas thus liberated absorbing the latent heat and producing an intense degree of cold, which, added to the refrigerating action of the holder itself, as above stated, will keep the safe and its contents so cold as for a long time to counteract the effect of external heat.

C indicates an interior gas-holder, essentially like the exterior ones, and designed to be readily inserted or removed at will, being placed either at the top or bottom or at one

or more sides of the safe. In practice it will be found well to place the holder at the top of the safe, as cold naturally descends, the outlet or vent being advisably at the middle, and provided with a valve, *c*, controlled by a fusible plug, block, or nut, *d*, outside of the safe, as in the patent above referred to.

In the drawings two forms of gas-holders are shown, either of which may be employed or replaced by others, provided only that they be made of convenient form for application to the safe, either outside or inside, without materially interfering with the size of the safe or its interior space. A flat form is of course desirable, because requiring but little room and possessing an extended surface. These holders may be applied in a variety of ways—as, for instance, being hung or bolted upon the walls, slid into grooves, or otherwise; but in all cases it will be found advantageous to make them portable and readily removable for charging, &c.

Having thus described my invention, what I claim is—

1. In combination with a safe or vault, an exterior gas-holder provided with a vent and a fusible seal, adapted to fit upon a wall or face of a safe or vault, applied thereto and adapted to be removed therefrom, substantially as explained.
2. In combination with a safe or vault, a flat gas-holder provided with a vent and a fusible seal, adapted to fit upon a wall or face of a safe or vault, applied thereto and adapted to be removed therefrom, substantially as explained.
3. A gas-holder for use in safes or vaults, made in a thin flat form, substantially as shown, whereby it is adapted to fit against the interior wall of the same, and, while exposing a large cooling-surface, not materially lessen or change the form of the space within the safe or vault, as set forth.

HENRY C. JOHNSON.
